UNITED STATES PATENT OFFICE.

LAWRENCE B. SPERRY, OF FARMINGDALE, NEW YORK; THE BANK OF AMERICA, OF NEW YORK, N. Y., AND WINIFRED ALLEN SPERRY, OF HEMPSTEAD, NEW YORK, EXECUTORS OF SAID LAWRENCE B. SPERRY, DECEASED.

MEANS FOR GUIDING AEROPLANES ON THE GROUND.

Application filed June 8, 1922. Serial No. 566,702.

To all whom it may concern:

Be it known that I, LAWRENCE B. SPERRY, a citizen of the United States of America, residing at Farmingdale, L. I., in the county 5 of Nassau and State of New York, have invented certain new and useful Improvements in Means for Guiding Aeroplanes on the Ground, of which the following is a specification.

10 This invention relates to aeroplanes, and particularly to means for controlling an aeroplane on the ground, especially when landing.

When an aeroplane is in flight and, of 15 course moving rapidly, its direction of travel is controlled by the manipulation of plane surfaces which are acted upon by the strong relative movement of the air. When landing, however, after the craft has reached 20 the ground and its speed becomes greatly reduced, the control planes become ineffective for steering. This, however, is not ordinarily of great importance, as it is customary when landing to head the craft directly 25 into the wind. This aids in bringing the craft to a quick stop and also obviates the necessity of steering it toward the end of its movements as there are practically no forces tending to divert the craft from a straight 30 course and as the landing field is large enough to permit the craft to wander.

A very different problem is presented, however, when landing is to be effected in a 35 restricted place, as for instance, on a street or other narrow piece of smooth ground. Under such conditions, the aviator is restricted in the direction in which he may head his machine and cannot choose his landing direction in accordance with the 40 direction of the wind. Consequently, if the wind is blowing at an angle to the aircraft when a landing is made, there is no way of keeping the craft on its narrow path after it has slowed down to the point where the 45 steering plane or rudder becomes ineffective, and the craft is free to travel or to be blown where it will.

The main object of the present invention 50 is to provide means whereby an aeroplane may be steered when on the ground, irrespective of its speed of travel.

Another object is to provide means in connection with the steering means for braking

the craft when the length of the landing space is also restricted.

Referring to the drawings wherein I have shown what I now consider to be the preferred form of my invention:

Fig. 1 is a perspective diagrammatic view 60 of the control elements of an aeroplane.

Fig. 2 is a side view of an aeroplane wheel with means for braking the same.

Fig. 3 is a plan view of the wheels with a modified means for actuating the brakes thereof.

Fig. 4 is a detail of one form of another form of brake actuating or steering means.

In the drawings the aeroplane fuselage is indicated in dotted lines 1 in Fig. 3, having the usual cockpit 2, within which is the aviator's seat 3. Secured to the fuselage in the usual manner, not shown here, are the supports 4 which carry the axle 5 which in turn carries the aeroplane wheels 6, 7.

In Fig. 1 the fuselage as well as the supporting planes are omitted so that the control elements may be more clearly portrayed. The usual ailerons are shown at 8, 9; the elevating control planes or horizontal rudders at 10, 11, and the vertical or steering rudder at 12. Said steering rudder may be mounted on an upright post 13.

The lower end of this post may constitute the usual tail skid and in this instance is shown as provided with a wheel 14. Near the forward end of the aircraft I have shown a control stick 15 pivotally attached at 16 to a bar 17. Said bar may in turn be mounted in bearings 18, 19, for rotation about its longitudinal axis but restricted against axial movement. Cords or wires

20, 21 may be connected at 22 to the stick 15 above its pivotal point 16 and to the lower ends of cross levers 23, 24 of elevating planes 10, 11, while wires 25, 26 are connected at 27 to the stick 15 below its pivotal point and to the upper ends of said levers 23, 24.

Thus, a forward thrust of the upper end of the control stick will tilt the rear part of planes 10, 11 downwardly 100 to cause the aircraft to descend, while a rearward thrust of said stick will effect the opposite results.

The bar 17 is shown as having an upwardly projecting lever arm 28 having attached to its upper end wires 29, 30 reach-

ing in opposite directions around pulley wheels 31, 32 to the upper ends of cross levers 33, 34, fixedly connected to ailerons 8, 9. The lower ends of said cross levers may be interconnected by a wire 35 passing around pulley wheels 36, 37. Thus movement of the control stick 15 to the right or left to turn bar 17 about its axis will effect actuation of the ailerons through wires 29, 30, 35 to tilt said ailerons in opposite directions one way or the other to control the transverse position of the aircraft.

The control of the vertical rudder 12 may be effected by means of a pedal 38 pivotally attached at 39 to a fixed portion 40 of the craft and connected on opposite sides of its pivotal axis by wires 41, 42, to the opposite ends of a cross lever 43 secured to the post 13.

20 The wheels 6, 7 are shown as provided with brakes 44, 45, which as shown in Fig. 2 may comprise a drum 46 integral with the wheel; a brake band 47 upon said drum; a bracket 48 rigidly connected with respect to the aircraft as by being fixedly attached to the axle 5; said brake band being attached at one end to a pin 49 integral with bracket 48, and at the other end 51 to a bell crank lever 50 pivoted at 52 to bracket 48. 25 The levers 50 of the two brakes 44, 45, may be connected by wires 53, 54, passing over pulley wheels 55, 56, to the control stick at 22. The wires 53, 54 may be loose as shown, if desired, so that normal movements 30 of control stick 15 to actuate the control planes may be effected with little or no pull upon said wires, but any further movement of the stick will pull upon one or both of the wires 53, 54, actuating lever 50 to draw the 35 brake band tight upon the brake drum. 40

The operation is as follows:

When in flight, the aviator will steer the craft with his feet by actuation of pedal 38. To cause the craft to ascend or descend, he 45 will tilt the stick backward or forward to tilt the horizontal rudders 10, 11 upwardly or downwardly. To control the transverse position of the craft, as in stabilizing against side air currents or in banking, the 50 stick is tilted to one side or the other to rotate bar 17 and actuate wires 29, 30 connected to the ailerons 8, 9. When running along the ground at a slow speed, when the rudder 12 is ineffective to steer the craft, 55 as for instance, when starting up for a flight, it will be seen that actuation of pedal 38 will effect the same result on the ground as in the air inasmuch as the rear skid or wheel 14 will be turned. When landing, 60 steering may be done in the same manner, but may also be done by thrusting the control stick 15 to one side or the other to apply brake 44 or 45 to retard the wheel on the side to which it is desired to turn. To 65 apply both brakes equally to bring the craft

to a quick stop, the stick may be thrust either forward or backward to pull equally upon both wires 53 and 54, while braking and steering may be effected simultaneously by thrusting the stick backward or forward to apply both brakes and at the same time moving the stick to one side or the other to apply with greater force the brake on the side to which the craft is to be steered.

One advantage of steering by differentially braking the landing wheels, is, then, as we have seen, that the craft may also be brought to a stop more rapidly. Another advantage is that by this method steering 75 may be commenced the moment the front wheels touch the ground and when the rear wheel 14 is still in the air. Of course, at such times the craft is usually traveling at such speed that the rudder 12 is still effective for steering and both methods may be employed. Also, after the rear wheel 14 touches the ground, steering may be effected by the turning of said wheel and by the differential braking of the front wheels. 80 Thus, the action of an aeroplane upon landing may be controlled with a high degree of refinement.

In Fig. 3 I have shown a modification in the actuating connections of the brakes. In this form, the pedal is shown in two parts 57, 58, both pivoted at 39'. A tension spring 59 connected between brackets 60 on the two parts may serve to normally hold the parts in the relative positions shown. The wires 41, 42 connecting the pedal to the rudder 12 and skid wheel 14 may include resilient sections 61, 62. The wires 53, 54 for actuating the brakes are shown as passing from the pulley wheels 55, 56 to the parts 57, 58 of the pedal. Steering in the air will be effected by pressure on one side or the other of the pedal in the usual manner. On the ground the same action will produce the same result. In other words, when in the air, the aviator presses upon the part 57 of the pedal to execute a turn to the right. On the ground, pressure upon part 57 brakes wheel 6 and causes the craft to turn to the right. In order to apply both brakes at the same time, the aviator may press upon both parts 57, 58 of the pedal. In this instance, he will of course press with sufficient force to cause the resilient members 61, 62, to yield.

In Fig. 4 I have shown a further modification. Here the vertical rudder wires 41, 42, are connected to the pedal 38 as in Fig. 1. The brake wires 53, 54 are also connected to the pedal and pass over pulley wheels 63 carried by the lever 15' pivoted at 16'. Said lever may be specially provided for braking purposes, or it may constitute the control stick as in Fig. 1. Normally, actuation of pedal 38 affects only the steering rudder, but when it is desired to apply the brakes, the

aviator will pull back upon the lever 15' to draw the wires 53, 54 tight. This will apply the brakes with equal pressure. By pulling the lever back and pressing on one side of the pedal, the brakes may be applied differentially for simultaneous braking and steering. By pressing one side of the pedal forward, and pulling back upon the lever to draw only one of wires 53, 54 tight but one of the brakes may be applied for steering, only.

In accordance with the provisions of the patent statutes, I have herein described the principle of operation of my invention, together with the apparatus, which I now consider to represent the best embodiment thereof, but I desire to have it understood that the apparatus shown is only illustrative and that the invention can be carried out by other means. Also, while it is designed to use the various features and elements in the combination and relations described, some of these may be altered and others omitted without interfering with the more general results outlined, and the invention extends to such use.

Having herein described my invention, what I claim and desire to secure by Letters Patent is,

30 1. In combination with an aeroplane having forward landing wheels and a pivotally mounted trail wheel, of separate brakes on said forward wheels, and a common means for differentially applying said brakes and turning said trail wheel whereby the aeroplane may be steered on the ground by the cooperative action of the trail wheel and differential application of the brakes.

2. In combination with an aeroplane, control surfaces therefor, means for actuating said surfaces, wheels for said aeroplane, brakes for said wheels, and means connecting said brakes to said actuating means, said brakes being adapted to be actuated by movement of said actuating means beyond a predetermined degree.

3. In combination with an aeroplane, control surfaces therefor, means for actuating said surfaces, wheels for said aeroplane, brakes for said wheels, normally inactive control connections between said brakes and said actuating means, and means whereby said connections are rendered operative after a predetermined degree of actuation of said actuating means.

4. In combination with an aeroplane having a steering rudder and landing wheels, of means for actuating said rudder, brakes for said wheels, normally inactive control connections between said brakes and said rudder-actuating means, and means whereby said connections are rendered operative at will.

5. In combination with an aeroplane having forward landing wheels, a steering rudder and a trail wheel turnable with said rudder, of separate brakes on said forward wheels, and a common means for differentially applying said brakes and turning said rudder and trail wheel whereby the airplane may be steered when landing on the ground by the cooperative action of the rudder, trail wheel and differential application of the brakes.

6. In combination, an aeroplane having elevation control means, transverse positioning means, wheels, brakes for said wheels, and a single operating member for actuating said first two means and said brakes.

7. In combination, an aeroplane having elevation control rudders, transverse positioning rudders, wheels, brakes for each of said wheels, and a single operating member for differentially actuating said rudders and said brakes.

8. In combination, an aeroplane having elevation control rudders, transverse positioning rudders, wheels, brakes for said wheels, an operating member operable in a plurality of planes, means whereby operation of said member in one plane actuates said first-named rudders, and means whereby operation of said member in another plane actuates said second named rudders and said brakes.

9. In combination, an aeroplane having elevation control rudders, transverse positioning rudders, wheels, brakes for said wheels, an operating member operable in a plurality of planes, means whereby operation of said member in one plane actuates said first-named rudders, means whereby operation of said member in another plane actuates said second-named rudders, and means whereby operation of said member in said other plane beyond a predetermined degree actuates said brakes.

In testimony whereof I have affixed my signature.

LAWRENCE B. SPERRY.
